[57] CLAIM

The ornamental design for a seat, substantially as shown.

DESCRIPTION

FIG. 1 is a front perspective view of a seat showing my design in the form of an armchair; and

FIG. 2 is a rear perspective view thereof;

FIG. 3 is a front perspective view of the design of FIG. 1 shown in the form of a settee; and

FIG. 4 is a rear perspective view of the design of FIG. 1 shown in the form of a couch.

Fig.1.

Fig.2.
